UNITED STATES PATENT OFFICE.

JOSEPH C. SANDERS, OF ST. LOUIS, MISSOURI, ASSIGNOR TO AMERICAN FOUNDRY & MANUFACTURING COMPANY, OF ST. LOUIS, MISSOURI, A CORPORATION OF MISSOURI.

FLOOR DRAIN.

Application filed February 10, 1922. Serial No. 535,595.

To all whom it may concern:

Be it known that I, JOSEPH C. SANDERS, a citizen of the United States, residing at St. Louis, Missouri, have invented a certain 5 new and useful Improvement in Floor Drains, of which the following is a full, clear, and exact description, such as will enable others, skilled in the art to which it appertains, to make and use the same.

10 This invention relates to drains of the kind that are used for carrying surface water off a floor, and particularly, drains that are adapted to be set in floors constructed of concrete or similar material that 15 is molded around the drain.

The object of my invention is to provide an adjustable floor drain that is equipped with an efficient means for producing a tight joint between the drain and a water-proofing element that is arranged between the foundation layer of the floor and the finishing coat or top layer of the floor.

Figure 1 of the drawings is a vertical sectional view of a floor drain constructed in 25 accordance with my invention; and

Figure 2 is an enlarged top plan view of a portion of the laterally-projecting flange on the sleeve of the drain, illustrating the scoriated surface on the top side of said flange.

30 Referring to the drawings which illustrate the preferred form of my invention. A designates the head piece of my improved drain and B designates a sleeve that carries said head piece and which is provided at its lower 35 end with an internally screw-threaded portion 1 into which a drain pipe (not shown) is adapted to be screwed, the head piece A being funnel-shaped in general outline and provided at its lower end with an externally 40 screw-threaded portion 2 that is screwed into the upper end of the sleeve B, thereby enabling the head of the drain to be set so that the upper edge of same will be flush with the top surface of the finished floor.

45 In order that the water proofing element C that is generally arranged between the foundation layer α and the finishing coat or top layer γ of the floor may be securely connected to the drain in such a way as to 50 eliminate the possibility of a leak developing at the point where the drain passes through said water proofing element, I have provided the sleeve B of the drain with a laterally-projecting flange D equipped in its 55 top face with an undercut groove 3 into

which the edge portion of the water proofing element is adapted to be inserted and locked by a key z , formed preferably from a substance that can be introduced into said groove while in a plastic condition and then 60 allowed to harden.

Preferably, the exterior of the head A and the top and bottom faces of the flange D on the sleeve B are scoriated so as to ensure the floor material adhering to these portions of the drain, said scoriated surfaces being formed preferably by rows of rectangular-shaped, tapered projections 4, spaced apart and arranged so that the projections of one row alternate with the projections of an adjacent row, as shown in Figure 2.

In installing the drain the collar B with the head A mounted therein is first arranged in the proper position and the material that forms the foundation layer α of the floor 75 is then molded around said collar and around the peripheral edge of the horizontally-disposed flange D thereon.

The water proofing element C, which may consist of various kinds of substances or 80 materials, is then arranged upon a foundation layer α , and the edge portion of said water proofing element is pressed downwardly into the undercut groove 3 in the top 85 side of the flange D, as illustrated in Figure 1 of the drawing. Thereafter, the groove 3 is filled with a self-hardening, plastic substance, so as to securely lock the down-turned edge of the water proofing element C and form a water-tight joint between same 90 and the flange D of the drain.

A floor drain of the construction above described is inexpensive to manufacture, it is easy to install, the material from which the floor is formed will cling tightly to the scoriated surfaces on the drain and the drain is of such design that the water proofing element imbedded in the floor will be securely connected to the drain in such a manner that it is impossible for seepage which collects 95 on said water proofing element to leak through the joint where the water proofing element is connected to the drain.

Having thus described my invention, what I claim as new and desire to secure by Letters Patent is:

A floor drain, comprising a sleeve adapted to be set in a molded floor and provided with a screw-threaded portion to which a drain pipe is adapted to be connected, a sub- 110

stantially funnel-shaped head provided with a part that is screwed into said sleeve, thereby enabling said head to be adjusted vertically so as to arrange the upper edge 5 of same flush with the top surface of the finished floor, a laterally-projecting flange on said sleeve, and an undercut groove in the top side of said flange that is adapted to receive the edge portion of a water proofing element embedded in the floor and also a locking key formed of a self-hardening substance, the exterior of the head of the drain and the top and bottom faces of said flange being scoriated, for the purpose described.

JOSEPH C. SANDERS.
